UNITED STATES PATENT OFFICE.

ALBERT J. GANZ, OF NEW YORK, N. Y., ASSIGNOR TO EINSON LITHO, INCORPORATED,
A CORPORATION OF NEW YORK.

DISPLAY DEVICE.

Application filed June 10, 1921. Serial No. 476,385.

To all whom it may concern:

Be it known that I, ALBERT J. GANZ, a citizen of the United States, residing in the city of New York, borough and county of Bronx, and State of New York, have invented certain new and useful Improvements in Display Devices, of which the following is a specification.

My invention aims to provide an improved container in which articles may be conveniently shipped and which may afterwards be opened in a way to display the contents attractively, the complete device being comparatively inexpensive.

The accompanying drawings illustrate an embodiment of the invention.

Figs. 1 and 2 are perspective views illustrating respectively the front and rear faces of the device in the open position for displaying the contents;

Fig. 3 is a transverse vertical section of the same;

Figs. 4 and 5 are horizontal sections on the correspondingly numbered lines of Fig. 3;

Fig. 6 is a perspective view of the device closed for shipment of the contents;

Figs. 7, 8 and 9 are blanks from which the container is formed;

Figs. 10 and 11 are perspective views of a modified design;

Fig. 12 is a blank for the same;

Figs. 13 and 14 are perspective and sectional views respectively showing the manner of assembling.

Referring to the embodiment of the invention illustrated, the device comprises a pair of pockets 1 and 2, the latter standing at an elevation above the former and offset backward therefrom so that each pocket may

carry a separate line of articles 3, both of which are easily visible from the front. The upper pocket 2 preferably also carries at the upper edge of its back a flap 4 upon which the name, price or other advertisement can be carried calling attention to the articles displayed.

The lower pocket 1 has a low front wall 5, end walls 6 and a high back 7, the upper part of which forms a low wall for the upper pocket; the upper pocket

having end walls 8 and a high back 9. The upper pocket is pivotally supported along the edge 10 of the back wall of the lower pocket. The lower side walls 6 have their forward edges vertical for a distance equal to the depth of the pocket and then offset

to the rear so that when the container is folded as in Fig. 6 the edges 11 of the sides 6 will substantially meet the edges 12 of the sides 8 and close the ends of the container. In this closed position the articles 3 in the upper and lower pockets, respectively, will lie end to end against each other and be carried snugly in the package.

The flap 4 is hinged along the dotted lines 13 and has a projecting tongue 14 which, when the flap is opened as in Fig. 1, is forced forward over the corresponding edge 15 of the back of the upper pocket and frictionally holds the flap in upright position; the natural tendency being for the upper portion of the flap to bend forward. When the device is to be used for shipping the flap 4 is bent down against the face of the back 9 and its corners pushed through the curved slots 16 to hold it flat; so that when the container is closed the flap 14 will overlie the front wall 5 of the lower pocket as shown in Fig. 6. In the shipping position, therefore, the articles are carried in a rectangular box, the ends of which are closed by the sides 8 and 6 of the pockets, the sides of which are closed by the backs 9 and 7 of the pockets and the ends of which are closed by the bottoms 17 and 18 (Figs. 3 and 6) of the pockets.

The device is held in the open position by means of a stiff brace 19 fastened on the back of the lower pocket and adapted to be collapsed into the dotted line position shown in Fig. 5 for shipping or to be extended to the full line position when the device is open so as to enlarge the base of the device and also to grip the upper pocket and hold it open against its natural tendency to swing forward. For the latter purpose the sides 20 of the brace are provided at their upper outer edges with tongues 21 forming shoulders for engagement with the back 9 of the upper pocket. In setting the device the upper part of the back 7 of the lower pocket will yield sufficiently to permit the back 9 of the upper pocket to be forced down inside the tongues 21, where it will be held by friction and by the weight of the articles in the upper pocket.

The device is made of any usual or suitable material, preferably stiff cardboard which will hold its shape and which will permit bending of the parts about the hinge lines necessary to close it for shipment and

to open it for display. It may be conveniently made of three pieces cut and slotted in the manner shown in Figs. 7, 8 and 9.

Referring to Fig. 7, at one end there is 5 the back 9 of the upper pocket, carrying the flap 4, the sides 8 of the upper pocket and certain tabs 22 to be used in fastening the parts together. See Fig. 4. Adjacent to one of the sides 8 is a side 6 of the lower pocket. Connected to the other edge of the side 6 is a part 7^a constituting an outer ply of the back of the lower pocket and carrying at opposite ends the two sides 6 of this pocket and certain tabs 23 at the lower ends 10 of said sides. See Fig. 5. Above the part 7^a is a strip 7^b which is to be folded back in the manner indicated in Fig. 3 to form part of the front wall of the upper pocket. Above this is a strip 18 forming the bottom 15 of the upper pocket and on the edge of the strip 18 is a long tab 24 which is bent up for attachment to and reinforcement of the 20 lower part of the back 9 of the upper pocket as shown in Fig. 3.

Extending from one of the side portions 25 6 is the strip 5 which constitutes the front wall of the lower pocket and adjoining this a strip 17 constituting the bottom of this pocket and a long tab 25 which is bent up 30 for attachment to and reinforcement of the lower pocket; the strip 5 carrying at its free end a tab 26 to be bent up against the inner face of the corresponding side wall of this pocket.

Similarly the strip 7^b has at one end a tab 27 to be bent up against the inner face of a side 8 of the upper pocket and fastened thereto. See Figs. 3 and 4.

Fig. 8 shows the sheet 7 which constitutes 40 the face-ply of the back of the lower pocket with a beveled extension 28 adapted to be folded over the parts 7^a and 7^b to reinforce the hinge, and having a further extension 29 (Fig. 3) for application to the bottom 45 of the upper pocket to stiffen this and hold the parts together.

Figs. 3, 4 and 5 indicate the manner of assembling these parts and it will be understood that they are fastened together by 50 glue or wire or other suitable fastening means so as to leave the two pockets and the flap 4 free to hinge in the manner described.

Fig. 9 is a blank for the brace 19 with its sides 20 and with tabs 30 for attachment 55 to the back of the lower pocket. The manner of folding is indicated by the dotted lines.

A construction in which the parts may be fastened together entirely by cutting and 60 folding, without the use of glue or fasteners, except for the brace at the back, is shown in Figs. 10 to 14. In this case the back 9 of the upper pocket has a strip 31 along one edge adapted to form the bottom 65 of the upper pocket, and at the outer edge

of this is a strip 32 adapted to be bent up against the front wall of the outer pocket. Instead of the tabs 26 and 27 of the previously described figures which were glued or otherwise fastened to the sides of the upper pocket, there is used in this modification extensions 33 and 34 from the front portion 7^b of the upper pocket and from the front portion 5 of the lower pocket, these extensions adapted to be bent back in the manner shown in Fig. 13 along the side wall of the corresponding pocket. That is, the extension 34 will be folded outside of the side wall 6 of the lower pocket and a fastening tab 35 on the end of said extension will be 75 folded first on the dotted line 36, Fig. 12, and then on the dotted line 37 to bring it to the shape shown in Fig. 13 and then will be passed through a registering slot 38 at the rear edge of the side wall 6 and will 80 be unfolded in the manner indicated in the left hand lower corner of Fig. 10. Similarly the extension 33 carries a tab 39 which will be folded transversely along the line 85 40 and then longitudinally along a line 41 and passed through a slot 42 in the rear edge of one of the side walls 8 of the upper pocket. These tabs inserted and then 90 unfolded in the manner described serve to unite the parts firmly and particularly to fasten the front wall of each pocket to the 95 rear wall of the same.

The supplementary piece 7 shown in Fig. 8 is practically a waste piece cut out of the upper left hand corner of the blank, 100 Fig. 7. The material of these boxes may be pasteboard with a right side which is smoothly finished and a wrong side which is rough and comparatively unattractive. In that case the part 7 being cut out from the blank will be turned so as to expose the right side, on which fine printing for 105 decoration or advertisement may be applied.

Fig. 11 shows a modification of the brace which consists of a pair of leaves 43 with shoulders at the top to hold the upper pocket, and with openings 44 on their inner edges; and a horizontally hinged leaf 45 is arranged with notches on its outer edge which in the horizontal position illustrated 110 115 will hold the leaves 43 vertical. When the leaf 45 is swung up flat against the back of the lower pocket its edges lie clear within the enlargement 46 of the aforesaid space and thus relieve the leaves 43 and permit 120 them also to be folded back outward. This is the position for shipping, and the parts of the brace are of the thickness of only one 125 ply against the back of the package, which is preferable to the two-ply arrangement of the brace shown in Figs. 2 and 3 when the box is ready for shipment.

Though I have described with great particularity of detail a specific embodiment of my invention yet it is not to be understood 130

therefrom that the invention is restricted to the particular embodiment disclosed. Various modifications thereof in detail and in the arrangement of the parts may be made 5 by those skilled in the art without departure from the invention as defined in the following claims.

What I claim is—

1. A display device comprising a pair of 10 pockets one standing above and back of the other and hinged together so that one may be folded over the other to form a closed package for the contents, said device including a single sheet extending over the back, 15 bottom and front wall of the upper pocket and the back of the lower pocket.

2. A display device comprising a pair of 20 pockets one standing above and back of the other and hinged together so that one may be folded over the other to form a closed package for the contents, said device including a single sheet extending over the back, 25 bottom and front wall of the upper pocket and the back of the lower pocket, and having integral portions forming the sides of both pockets.

3. A display device comprising a pair of

pockets one standing above and back of the other and hinged together so that one may be folded over the other to form a closed 30 package for the contents, said device including a single sheet extending over the back, bottom and front wall of the upper pocket and the back of the lower pocket, and having integral portions forming the sides 35 of both pockets and also portions forming the bottom and front wall of the lower pocket.

4. A display device comprising a pair of 40 pockets one standing above and back of the other and hinged together so that one may be folded over the other to form a closed package for the contents, said device including a single sheet extending over the back, 45 bottom and front wall of the upper pocket and the back of the lower pocket, and a second sheet overlying the portion of the first sheet which forms the front wall of the upper pocket and the back wall of the lower pocket.

In witness whereof, I have hereunto signed my name.

ALBERT J. GANZ.
